UNITED STATES PATENT OFFICE.

JOSEPH K. JOHNSTON AND WILLIAM B. JOHNSTON, OF ANDERSON, INDIANA.

APPARATUS FOR FORCING WATER, &c., FROM NATURAL-GAS OR OTHER WELLS.

SPECIFICATION forming part of Letters Patent No. 554,188, dated February 4, 1896.

Application filed July 18, 1895. Serial No. 555,856. (No model.)

To all whom it may concern:

Be it known that we, JOSEPH K. JOHNSTON and WILLIAM B. JOHNSTON, citizens of the United States, and residents of Anderson, in 5 the county of Madison and State of Indiana, have invented certain new and useful Improvements in Apparatus for Forcing Water and other Liquids from Gas or other Wells; and we do declare the following to be a full, 10 clear, and exact description of the invention, such as will enable others skilled in the art to which it appertains to make and use the same, reference being had to the accompanying drawing, and to letters of reference 15 marked thereon, which forms a part of this specification.

The figure of the drawing is a vertical sectional view of the invention.

This invention has relation to apparatus 20 for forcing water or other liquids from natural-gas wells, and is designed to provide means of improved character wherein the pressure of the gas is used to force the water to the top of the well.

25 The invention also provides means whereby the gas and water pipes may be cleared when necessary.

With these objects in view the invention consists in the novel construction and combination of parts, all as hereinafter described and pointed out in the appended claim.

Referring to the accompanying drawing, the letter A designates the drive-pipe of a natural-gas well, which is driven through the 35 soil, sands, and drift to the limestone rock upon which it rests, as indicated.

B designates the casing, which extends from the top of the well through the drive-pipe down to the shale rock upon which it rests, 40 as shown. Below this pipe the rock constitutes the wall of the well. Said pipe is usually from five to five and five-eighths inches in diameter.

C designates the water discharging or separator pipe, which extends from above the ground to the bottom of the well, its lower portion C' being perforated to admit water.

c is a stop-cock at the upper portion of the pipe C.

50 D is the gas-pipe which surrounds the water-pipe C and extends from above the ground

to the bottom of the well, its lower portion D' being perforated. The upper end of the pipe D is connected by a coupling D² to a pipe D³ D⁴, which is connected to a gas-main E which 55 has other wells (not shown) also connected thereto.

F is a stuffing or packing box for the pipe C, where it passes out of the coupling D², said box having a nut F' and packing f of hemp 60 or like material, upon which the nut seats.

G is a small pipe which connects the pipe D³ with the pipe C and is for the purpose of admitting gas to the latter to blow it out whenever the perforations at the bottom thereof 65 become clogged or choked.

g is a cock in said pipe.

g' is a gate-valve in the pipe D³.

H is a blow-off for the pipe D, and h is the valve thereof.

I is a packer which is placed around the pipe B just above the line of the Trenton or gas-bearing rock, and which confines the water and gas below it.

The operation is as follows: By closing the 75 gate-valve g' and opening the valve c there will commonly be pressure enough in the well to force the water into the pipe C and raise it to the surface and discharge it. It frequently happens, however, that after a well 80 has been flowing for some time, the pressure of the gas becomes too weak to accomplish this result. When this occurs the valves c and g' are opened, and the gas from the main E flows down the pipe D into the bottom of 85 the well, and being confined below the packer D creates a pressure sufficient to force the water into pipe C and discharge it. The well being cleared of water the valve g' is left open, and the gas in the well rises into the 90 main E.

By opening the valve g at any time the pipe C may be blown out.

By opening the valve h the pipe D may be blown out.

Having thus described our invention, what we claim as new, and desire to secure by Letters Patent, is—

The combination of the gas-discharging pipe D, which extends to the bottom of the 100 well, its lower portion being perforated and its upper portion connected to a gas-main

which is also connected to other wells, the water-discharging pipe C which extends through the said pipe D to the bottom of the well, and is perforated at its lower portion, 5 the packer I which surrounds the pipe D, a valved pipe which connects the main connection of pipe D, with the upper portion of the pipe C, a valve for closing the discharge of the pipe C, and a blow-off H for the pipe D, 10 all combined and arranged to operate sub-

stantially in the manner and for the purpose described.

In testimony whereof we affix our signatures in presence of witnesses.

JOSEPH K. JOHNSTON.
WILLIAM B. JOHNSTON.
